United States Patent Office

Des. 231,156
Patented Apr. 9, 1974

231,156

SLIPPER

Takayuki Ozawa, Tokyo, Japan, assignor to Shinko Co.,
Ltd., Chuo-ku, Tokyo, Japan

Filed June 2, 1972, Ser. No. 259,366

Term of patent 14 years

Claims priority, application Japan Dec. 3, 1971

Int. Cl. D2—04.

U.S. Cl. D2—279

FIG. 1 is a top plan view of a slipper showing my new design;

FIG. 2 is a side elevational view thereof;

FIG. 3 is a front elevational view;

FIG. 4 is a rear elevational view; and

FIG. 5 is an elevational view of the side opposite that shown in FIG. 2.

I claim:

The ornamental design for a slipper, as shown.
